UNITED STATES PATENT OFFICE.

MOYLAND E. COURTNEY, OF FAIRPLAY, MISSOURI.

MOTOR-PLOW.

1,112,267.

Specification of Letters Patent. Patented Sept. 29, 1914.
Application filed December 28, 1912. Serial No. 739,099.

To all whom it may concern:

Be it known that I, MOYLAND E. COURTNEY, a citizen of the United States, residing at Fairplay, in the county of Polk and State 5 of Missouri, have invented new and useful Improvements in Motor-Plows, of which the following is a specification.

This invention relates to motor plows, the object in view being to provide a motor 10 driven plow or other agricultural implement, in which an internal combustion motor of any suitable type may be employed for imparting motion to a traction drive wheel, by means of which the frame of the 15 machine, together with the operative parts thereof, is propelled along the field.

One of the principal objects of the invention is to provide means whereby when 20 the plow or other implement comes into contact with an obstacle, the motor will be thrown out of operative connection with the driving wheel of the machine, causing the machine to stop without breaking the plow beam.

25 A further object of the invention is to provide means within reach of the driver, whereby the direction of rotation of the driving wheel of the machine may be instantly reversed, without reversing or stopping the operation of the motor.

With the above and other objects in view, the invention consists in the construction, combination and arrangement of parts, as 30 will be hereinafter more fully described, 35 illustrated in the accompanying drawings, and pointed out in the claims hereunto appended.

In the drawings: Figure 1 is a side elevation of a motor driven plow, embodying the 40 present invention. Fig. 2 is a plan view of the same. Fig. 3 is an enlarged sectional plan view of the clutch. Fig. 4 is a detail vertical section illustrating the plow raising and lowering mechanism. Fig. 5 is a 45 front elevation of the front axle.

The motor plow contemplated in this invention comprises an open center main frame or chassis, comprising the longitudinal bars 1 and 2, rear cross bar 3, and a 50 suitable number of intermediate cross bars to give the required rigidity to the frame as a whole. At the forward portion of the frame is the front axle 4 which is connected rigidly to the side bars 1 and 2, and is provided with pivoted and swinging steering

knuckles 5, carrying the front steering wheels 6 which are journaled on the spindles of the knuckles, the knuckles being pivotally connected, at 7, to the rigid portion of the axle, so as to swing on vertical axes. 60

Connected to the inner end portions of the knuckles are the arcuate bars 8 forming bearings for the steering knuckles, and extending backward therefrom are arms 9 which are coupled together by a connecting 65 rod 10. A crank arm 11 has a jointed connection with the connecting rod 10, and extends downwardly from the forward end of a steering rod 12 in the form of a rock shaft mounted in suitable bearings 13 and 14, and provided at the rear with a controlling hand wheel 15 arranged just in front of a combined seat and gasoline tank 16 located at the rear of the frame and supported by the side bars 1 and 2. 70

17 designates pendant U-shaped hangers which secure the front axle 4 to the frame of the machine. 75

In addition to the support obtained by the front steering wheels 6, the rear portion 80 of the frame of the plow is carried by a traction drive wheel 18 provided on its outer periphery with suitable traction ribs 19. The drive wheel is mounted on an axle 20, and fast on and rotating with the drive wheel 85 is a gear wheel 21 which meshes constantly with an intermediate transmission gear wheel 22 mounted on a counter shaft 23 parallel to the axle 20, as shown in Fig. 2.

Mounted on the frame of the machine, 90 in advance of the driving wheel 18, is an internal combustion motor, 24 designating the cylinder of the motor, and 25 the fly wheel thereof. The shaft 26 of the motor is mounted in a suitable supporting frame 95 27 attached to the main frame of the machine, and said shaft 26 is also journaled in the rear upper extremities of parallel braces 28 which extend forward and connect rigidly to the machine frame, as shown 100 in Fig. 1. The braces 28 are provided; intermediate their ends, with upward extensions 29 provided with slots 30 described in the arc of a circle, of which the shaft 26 is the center. 105

The shaft 23 of the transmission gear 22 is movable lengthwise of the slots 30, and is mounted in bearings in the lower rear ends of the side bars 31 of a pivoted and swinging frame, said frame being pivotally 110

mounted, at 32, intermediate its ends. In the upper rear ends of the frame bars 31 there is journaled a reversing pinion 33 which is adapted to be moved into and out 5 of engagement with a drive pinion 34 adapted to be thrown into and out of engagement with the shaft 26 of the motor. It will be observed at this point that when the frame 31 is rocked on its pivot, the reversing pinion 33 is moved toward and away from the driving pinion 34, and simultaneously therewith the transmission gear 22 is moved into and out of mesh with the driving pinion 34. The transmission gear is always in mesh 15 with the driving gear 21, and also with the reversing pinion 33, but said transmission gear is thrown out of mesh with the driving pinion 34 when the reversing pinion 33 is thrown into mesh with said driving 20 pinion.

A hand lever 35, rod 36, lever 37, and link 38 may be employed for moving the reversing frame 31 on its fulcrum, or any other suitable or convenient means may be employed for that purpose, the same being under the manual control of the operator in his seat on the machine.

The shaft 26 of the motor is connected by a suitable coupling 39 to a jack-shaft or 30 clutch shaft 40 arranged in longitudinal alignment therewith and forming an end extension thereof. Mounted on the shaft 40 is the driving pinion 34, ball bearings being preferably used for such mounting. Connected fast to the pinion 34 is a female clutch member 41, around which is placed a band brake 42 of the construction now in common use with automobiles, and having suitable connections leading back to the operator's 40 seat, to enable the operator to apply and release the brake. The pinion 34 and the clutch member 41 are both normally loose on the shaft 40 which is constantly rotated by the motor. The end portion of the shaft 40 45 has loosely mounted thereon a belt pulley 43, the hub of which bears against a collar 44 fast on the shaft 40, as shown in Fig. 3. At its inner end, the pulley 43 is provided with a female clutch face 45 arranged at a suitable 50 distance from the female clutch member 41, hereinabove described. Between the two female clutch members is arranged a double male clutch member, having the two beveled clutch portions 46 and 47, the part 55 46 being adapted to coöperate with the clutch member 41, while the part 47 is adapted to coöperate with the clutch member 45. These two clutch faces 46 and 47 are formed on a common hub which is provided with a 60 groove 47', the purpose of which will herein-after appear. Normally, the male clutch member is pressed inward into engagement with the clutch member 41 by means of a thrust spring 48 which is coiled around the 65 shaft 40 between the hub of the pulley 43 and

the male clutch member. When the male clutch is thrust outwardly by means, herein-after described, it serves, on account of being feathered to the shaft 40, to take up the belt pulley 43 and cause the same to rotate with the shaft 40 which is driven by the engine shaft. 70

In some cases, it is desirable to lock the belt pulley 43 to the shaft, so that it may constantly turn and act in the capacity of a fly wheel for the shaft of the motor. In order to accomplish this, I provide a sliding key 49, which passes through a suitable guide on the outer face of the fixed collar 44, as shown in Fig. 3, the inner end of said key 80 being adapted to be held in a socket in the hub, as shown, by means of a spring 50 exerting an inward thrust on said key. 85

The hub of the clutch member 47 is grooved at 47' to receive the fork of a bell-crank shifting lever 51, from which a suitable connection 52 extends back to a lever mounted on the dash-board 53 arranged in front of the driver's seat, as shown in Fig. 1. Another bell-crank shifting lever 54 is connected to the hub of the male clutch member, and is connected to a lever 55 fulcrumed, at 56, intermediate its ends on the machine frame, and provided in its opposite end with a set screw 57 which passes through the end of the lever, so as to contact with a trip arm 58 on a forwardly extending plunger rod or stem 59 connected at its rear end to the front yoke bar 60 which connects a pair of plow beams 61 and 62 arranged at opposite sides of the center of the machine and out of line with the track of the drive wheel 18. 90

The stem or plunger rod 59 constitutes a draw bar for the plows, and is mounted for a limited longitudinal movement, so as to bring the trip arm 58 into engagement with the set screw 57, the latter being adjustable, and said rod 59 is normally held forward but allowed to yield backward by means of a coiled compression spring 63 encircling 105 the rod 59, and mounted between a shoulder on said bar and a fixed shoulder on the machine frame. 110

The oppositely arranged plow beams 61 and 62 are connected at suitable points with cross bars 64 and 65, so that the plows and beams are adapted to move together as a unit. Therefore, when one of the plows meets an obstruction, the plows all move rearwardly, thereby causing the trip arm 58 to come into contact with the lever 55, which throws the clutch out, and thereby disconnects the engine from the drive wheel 18. 115

This avoids injury to the machine, and the operator may then reverse the machine and back away from the obstruction a sufficient distance to make a new start. 120

Extending upwardly and rearwardly from the rear cross bar connecting the plow beams is a tail guide 66 which passes between 125 130

guide rollers 67 on the machine frame. The plows are thus elevated as they move rearward.

The plows are adapted to be raised and lowered by means of parallel crank shafts 68 journaled on the opposite side bars 1 and 2 of the machine frame, and also journaled in the plow beams, said crank shafts being operated by means of a rod 70 which leads back 10 and is connected to an operating lever 71 arranged within reach of the driver. 72 designates a suitable housing or cab which may be employed to protect the mechanism and the operator.

15 From the foregoing description, it will be seen that by means of the construction hereinabove described, the driver may set the machine to move either forward or backward. In case one of the plows meets an 20 obstruction, the clutch is automatically thrown out and the motor is disconnected from the driving wheel of the machine, thus bringing the machine to a quick stop and avoiding injury to the plows and other 25 mechanism. The driver may then swing the reverse frame 31, so as to throw the pinion 33 into engagement with the pinion 34, at the same time throwing the transmission 30 gear 22 out of engagement with the driving pinion 34. By then letting in a clutch, the machine will be driven backward. With the aid of the steering mechanism, hereinabove described, the driver may direct the 35 machine to any desired point, making the turns at the ends of the rows, and otherwise manipulating the plow in a manner similar to the ordinary automobile, now in common use.

What is claimed is:

40 1. In a traction engine, an open center frame, an element pulled by the tractor, a centrally arranged traction drive wheel, a front axle, steering wheels connected therewith, a driving pinion on the motor shaft, a gear wheel fast on the axle of the drive wheel, a transmission gear wheel meshing with the drive wheel gear, a reversing pinion meshing with the transmission gear, and

means thrown into action by relative movement of the frame and the element pulled 50 by the tractor on meeting an obstruction operating to disengage the driving pinion from its shaft and throw the driving mechanism out of gear.

2. In a traction engine, an open center 55 frame, an element pulled by the tractor, a centrally arranged traction drive wheel, a front axle, steering wheels connected therewith, a driving pinion on the motor shaft, a gear wheel fast on the axle of the drive 60 wheel, a transmission gear wheel meshing with the drive wheel gear, a reversing pinion meshing with the transmission gear, and means thrown into action by relative movement of the frame and the element pulled 65 by the tractor on meeting an obstruction operating to disengage the driving pinion from its shaft and throw the driving mechanism out of gear, a pivoted frame by which the transmission gear and reversing pinion are 70 carried, and manually operated means for swinging said frame.

3. In a traction engine, an open center frame, an element pulled by the tractor, a centrally arranged traction drive wheel, a 75 front axle, steering wheels connected therewith, a driving pinion on the motor shaft, a gear wheel fast on the axle of the drive wheel, a transmission gear wheel meshing with the drive wheel gear, a reversing pinion 80 meshing with the transmission gear, a trip arm connected with the element pulled by the tractor, a clutch for throwing the driving pinion and reversing pinion alternately into and out of engagement with the motor 85 shaft, and a clutch operating lever arranged in the path of said trip arm and adapted to be actuated thereby when the element pulled by the tractor meets an obstruction.

In testimony whereof I affix my signature 90 in presence of two witnesses.

MOYLAND E. COURTNEY.
